UNITED STATES PATENT OFFICE.

ALLEN W. BODELL, OF WILMETTE, ILLINOIS.

DISH-WASHING MACHINE.

No. 821,696.

Specification of Letters Patent.

Patented May 29, 1906.

Application filed July 12, 1905. Serial No. 269,282.

To all whom it may concern:

Be it known that I, ALLEN W. BODELL, a citizen of the United States, residing at Wilmette, in the county of Cook and State of Illinois, have invented new and useful Improvements in Dish-Washing Machines, of which the following is a specification, reference being had to the accompanying drawings, forming a part thereof.

The purpose of this invention is to provide improved means for cleansing dishes with the minimum handling.

It consists of the features of construction set out in the claims.

In the drawings, Figure 1 is a plan view of my improved dish-washer. Fig. 2 is an end elevation of the same. Fig. 3 is a section at the line 3 3 on Fig. 1. Fig. 4 is a section at the line 4 4 on Fig. 1. Fig. 5 is a detail section at the line 5 5 on Fig. 4. Fig. 6 is a detail plan view of a basket-engaging fitting. Fig. 7 is an edge view of the partly-formed blank, which when completely formed enters into the vaned wheel for throwing the water.

In general the device shown in the drawings comprises a receptacle A, represented as made of sheet metal, through which the dishes are carried on a longitudinal track along one side and exposed to the successive showers of water thrown by revolving wheels from the other side of the receptacle, which is somewhat deeper, so that the water has greater depth and is taken up in sufficient quantity to be thrown, as described, onto the dishes as they pass alongside the row of such wheels. A frame structure, represented by the supporting-legs 1 and sills 2 2 2, carries the tank A. A shaft B extends longitudinally through the tank at one side of the middle of its width, being rotated by power applied to the band-wheel 3. On the shaft outside the tank is a sprocket-wheel 4, from which a chain 5 drives the sprocket-wheel 6, also mounted outside the tank. A crank-wrist 7 on the wheel 6 engages the slot 8 in a rocking lever 9, fulcrumed at its foot on the floor. From the lever 9 a link 10 extends to the lever-arm 11 of a vertical rock-shaft 12, which has a second longer lever-arm 13 extending at

about a right angle to the lever-arm 11 and connected by a link 14 with the basket-feeder 15. This basket-feeder is a plate having lugs 15^a, by which it is mounted for moving on the angle-iron tracks 16, which extend longitudinally through the tank parallel with the shaft B.

Guards 17 17 are secured by their vertical flanges to the vertical flange of the angle-iron tracks 16 and have their horizontal flanges overhanging the lugs 15^a, as seen in Fig. 5. The feeder 15 has two trip-dogs 18 pivoted to it and counterweighted below the pivot, so as to tend to stand erect and checked against the said feeder in one direction, so that they are free to tilt in the other direction to horizontal position. On the tracks 16 there are mounted the aerial carriers or baskets 20. These baskets have any open construction to permit free-drainage of water through them, and they are provided with cross-bars 21 21 21 at opposite ends and middle of the bottom, which rest upon the tracks 16 and are engaged by the trip-fingers 18, the distance from cross-bar to cross-bar 21 being substantially the length of the stroke of the link 14, derived from the rocking of the vertical shaft 12. With this construction it will be seen that for each rotation of the wheel 6 the feeder 15 will make a reciprocation, the trip-fingers 18 engaging a cross-bar of the basket in the forward movement of the feeder and tilting to pass the next preceding cross-bar in the retracting movement, and so becoming engaged with that preceding bar for the next forward movement, and it will be seen that successive baskets on the track, each pushing the one in front of it, will be fed with step-by-step movement through the structure and out at the delivery side onto the receiving-table 27, which has proper inclination to drain back into the receptacle and which may be extended to any convenient length. When the basket has the three cross-bars for engagement of the feeding-dog, two strokes are necessary to move the basket the whole length, and preferably the stroke corresponds to the width of the compartments from which water is thrown, as more particularly hereinafter described; but I do not limit myself to this. The basket may be in any form suitable for the purpose. They are designed to have the end cross-bars 22 22 and the upper middle cross-bar 23 notched to engage the edges of plates or dishes, so as to hold them securely in position and out of contact with each other, as seen in Figs. 1 and 4. Different forms of structure for engaging different shapes of dishes may be provided for the same general purpose, and for miscellaneous dishes all special devices for holding dishes in any particular position may be omitted, and in any event, even

when the notched bars are present, dishes of various forms may be lodged in the basket without regard to the form of the latter.

The shaft B overhangs the deeper portion 5 of the receptacle alongside the path of the baskets on the tracks 16, and mounted on the shaft B are a plurality of wheels C C C, which are preferably made with dished vanes or paddles 25 25, (see Fig. 3,) embraced between the heads or disks 35 35 to form buckets, and which are revolved with the concave face of the paddles forward, so that the buckets dip the water from the receptacle and throw it from the upper side of the wheel over onto the baskets and their contents. The receptacle is partitioned between the several walls, so that each wheel has its own separate compartment from which to dip the water. These compartments preferably communicate successively by apertures 26 through the partitions 26 at the bottom. The water is supplied hot from a pipe D into the last compartment and passes back from compartment to compartment only through 25 the apertures 26*, so that the successive compartments have successively cooler water. A constant discharge may be allowed from the first compartment (that which the water reaches last) to prevent overflow, a discharge-port being provided controlled by a stopper 27.

The "aerial" carriers are so called because they move in a path above and out of the water, and likewise the dishes carried thereby, and thus the water taken by the paddle-wheels from different sources is thrown over and against the dishes and flows off the same. Each paddle-wheel is supplied with water received in the compartment of that particular paddle-wheel, and therefore the paddle-wheels are supplied with water from different sources. For instance, the water of one source will ordinarily be hotter than that of another source, and the different sources will also probably differ with respect to the cleanliness of the water. The water arriving at the first compartment, from which it is thrown onto the newly-arriving soiled dishes, is hot enough for cleansing purposes, though cooler than the rinse-water, which is that delivered directly from the pipe leading to the final compartment, and the temperature at this point is designed to be such that the dishes will dry from their own heat without wiping as soon as the rinse-water drains from them.

55 A cover 30 is provided to close the receptacle at the top and confine the water thrown by the wheels, which would otherwise be distributed widely on account of the tangential movement which it receives from the wheel. The receptacle has a ledge 31, formed as a crimp or fold near the top, extending on all four sides, upon which the cover 30 lodges, and the cover has a flange 32, which extends down inside the ledge and prevents the water being driven out around the margin of

the cover. The cover is conical in form, as seen in Figs. 3 and 4, and the ledge 31 is a sufficient distance below the upper margin of the receptacle to leave a considerable pocket above the cover when it is in place, so that any water which is forced past the ledge has opportunity to drain back into the receptacle. 70

The particular structure of the wheels adapts them especially for their purpose. They are each made of a continuous strip of metal folded upon itself to form projecting vanes at the intervals at which such vanes are to occur in the circumference of the wheel, the entire strip with these projecting 80 vanes being then joined end to end to make the wheel, the vanes, consisting each of a two-ply fold, being curved, as shown, after being folded, and in order that the body of the wheel—that is, that from which the 85 vanes project when the wheel is completed—may be regularly cylindrical the ply of each fold which is to be at the concave side of the vane when it is completed is made enough shorter than the other ply so that when the 90 vane is curved the difference between the two plies may be taken up, the inner one sliding on the outer one to bring the heels or angles of junction of the plies with the body portion together. Fig. 7 shows the portion 95 of the strip folded as described to form the vanes before the vanes are curved or the strip joined up endless to make the complete wheel, and in this figure may be seen the extra length of what is to be the outer ply. 100 The element comprising the cylindrical body, with the curved vanes made, as described, of a single piece folded and curved and joined up endless, as stated, is inclosed between two heads or disks 35 35, by which the intervals 105 between the consecutive vanes become pockets, and the necessary flanges 36 for securing the paddle-wheels to the shaft are mounted on these disks or heads 35 at the center.

I claim—

1. A dish-washer comprising an aerial carrier for the dishes; means for moving said carrier; a plurality of paddle-wheels arranged alongside the path of the carrier; different water-sources from which the paddle-wheels are supplied; and means for rotating the paddle-wheels and causing them to throw over and onto the contents of the carrier. 110

2. A dish-washer comprising a water-receptacle; a plurality of paddle-wheels arranged in a row; dish-carrying mechanism consisting of a track located alongside the row of paddle-wheels and running parallel with the axes of the paddle-wheels; a carrier 120 supported on said track; step-by-step feed mechanism for engaging the carrier to advance it along the track; means for supplying the paddle-wheels with water, and means 125 for rotating them toward the carrier at the 130

upper side for throwing the water onto the dishes.

3. A dish-washer comprising a dish-carrying mechanism, consisting of a track; baskets supported on the track; step-by-step feed mechanism for engaging the baskets to advance them along the track; a plurality of paddle-wheels having their axes parallel with the track and located alongside thereof; means for supplying the paddle-wheels with water and means for rotating them toward the baskets at the upper side for throwing the water onto the dishes.

4. A dish-washer comprising a dish-carrying mechanism consisting of a track; baskets adapted to be supported and moved on the track; mechanism for advancing them therewith step by step with halting intervals between the successive steps; a plurality of paddle-wheels arranged successively alongside the track respectively opposite the halting positions of the baskets; means for supplying the paddle-wheels with water and for rotating them over toward the baskets at the upper side to throw water onto the dishes from the latter.

5. A dish-washer comprising a dish-carrying mechanism, consisting of a track; racks or baskets for holding the dishes lodged upon and adapted to be advanced along the track; mechanism for so advancing them; a receptacle in which both the track and the paddle-wheels are contained, having at the lower part compartments for the wheels respectively; means for supplying water to the last receptacle along the path of the dishes, said receptacles having communication successively from the last back to the first, and means for rotating the paddle-wheels in direction to carry them over toward the racks or baskets at the upper side for throwing the water from the receptacle onto the dishes.

6. In a dish-washer in combination with a receptacle for water, a dish-carrying mechanism comprising a track extending through said receptacle along one side; dish-carrying racks or baskets lodged on the track and adapted to be moved therewith; a feeder reciprocating under the path of the baskets having trip devices for engaging said baskets in one direction, adapted to be retracted idly under them in the opposite direction for advancing them step by step along the track, and means for showering water onto the dishes while they are thus advanced.

7. In a dish-washer, in combination with a receptacle for cleansing fluid; a track extending through said receptacle along one side; racks or baskets for carrying dishes mounted on and adapted to be advanced along the track; a shaft extending parallel with the track overhanging the receptacle; a plurality of paddle-wheels mounted on the shaft; means for revolving the shaft to cause the

paddle-wheels to revolve over toward the track at the upper side for dipping the fluid from the receptacle and showering it onto the dishes, said receptacle being partitioned at the lower part to form separate compartments in which the paddle-wheels respectively dip; means for supplying fluid to the last of said compartments along the path of advance of the dish-carrier, said compartments having communication with each other for receiving the fluid, successively, from the last back to the first along the path.

8. In a dish-washer, in combination with a receptacle having compartments at the lower part for cleansing fluid; a track extending along one side of the receptacle; means operating on the track for advancing the dishes therewith; paddle-wheels dipping in the compartments respectively; means for revolving the wheels with the vanes concave side forward and toward the track at the upper side for dipping up the fluid from their respective compartments and throwing it onto the dishes.

9. In a dish-washer, in combination with a receptacle having compartments at the lower part at one side for cleansing fluid; a track extending along the other side of the receptacle, the receptacle being extended at both ends at that side; racks or baskets for holding the dishes, mounted on the track and adapted to be moved therewith from the extended portion at one end past the compartments and into the extended portion at the other end, and means for so moving them; paddle-wheels in the compartments respectively and means for revolving them in direction to cause them to dip the fluid from their respective compartments and throw the fluid from the upper side over onto the racks or baskets.

10. In a dish-washer, in combination with a receptacle, the track extending along one side thereof, said receptacle having at the other side, opposite the middle portion, a plurality of compartments; a shaft extending parallel with the track above said compartments; paddle-wheels on the shaft revolved thereby in the several compartments; a reciprocating feeder having trip-fingers for engaging the carrier and actuating the same in one of the directions of its reciprocation, and operating connections from the shaft for actuating the feeder.

11. In a dish-washer, in combination with a receptacle, a track extending along one side thereof, said receptacle having at the other side opposite the middle portion a plurality of compartments; a shaft extending parallel with the track above said compartments; paddle-wheels on the shaft revolved thereby, each in its own compartment; a dish-carrier on the track; a feeder for actuating it, and operating connections from the shaft to the feeder.

12. In a dish-washer, in combination with a receptacle, a track extending along one side thereof, said receptacle having at the other side, opposite the middle portion, a plurality of compartments; a shaft extending parallel with the tracks above said compartments; paddle-wheels on the shaft revolved thereby, each in a separate compartment; a carrier; a reciprocating feeder having trip-fingers for actuating the carrier in one of the directions of its reciprocation; a crank-wheel and connections for rotating it; a rocking lever connected with the crank, and a link or pitman connected with such lever and with the feeder for reciprocating the latter.
13. In a dish-washer, a liquid-receptacle having a plurality of liquid-compartments arranged in a row and divided from each other; a plurality of paddle-wheels rotatably mounted, each in a separate one of said compartments; a track extending parallel with the row of compartments and the axes of the paddle-wheels therein; a carrier movable along said track; means for moving the carrier along the track and subjecting the contents thereof successively to the paddle-wheels which dip the liquid from their respective compartments and throw the same over onto the dishes.
14. A dish-washer comprising a liquid-receptacle; a row of compartments or stalls therein; a dish-carrier movable in front of the several compartments or stalls; paddle-wheels arranged each in one of said compartments or stalls, and means for actuating said wheels and causing them to dip the liquid from their respective compartments or stalls and shower the same over the dishes as the

carrier arrives in front of the compartments or stalls.

15. A dish-washer comprising a liquid-receptacle; a row of compartments or stalls therein; a dish-carrier movable in front of the several compartments or stalls; paddle-wheels arranged each in one of said compartments or stalls; means for actuating said wheels and causing them to dip the liquid from their respective compartments or stalls and shower the same over the dishes as the carrier arrives in front of the compartments or stalls; and means for conducting the liquid from one compartment or stall to another without coming in contact with the dishes.

16. A paddle-wheel for a purpose such as indicated, made from a strip of metal folded upon itself at intervals to form offsetting two-ply flanges, and connected end to end, and heads or disks abutting on the lateral edges of the flanged element.

17. A paddle-wheel for the purpose indicated, comprising a middle element consisting of a single strip of metal folded upon itself at intervals to form two-ply flanges and having its ends joined, the two-ply flanges being curved concavo-convex all in the same direction, and heads secured to said metal element at opposite sides abutting on the ends of the flanges.

In testimony whereof I have hereunto set my hand, at Chicago, Illinois, this 8th day of May, A. D. 1905.

A. W. BODELL.
In presence of—
CHAS. S. BURTON,
M. GERTRUDE ADY.
